RERAILER

Joseph Herman Perks, Sr., Henrico County, Va.

Application March 22, 1948, Serial No. 16,208

7 Claims. (Cl. 104—268)

1

This invention relates to rerailers or devices for replacing railroad locomotives and cars upon the tracks.

It is an object of the invention to provide a rerailer which will operate to smoothly and gradually lift the wheels to the level of the tracks and deposit the wheels thereupon substantially without a drop, shock or jar.

A second object is to provide a rerailer in which the inside and outside parts are substantially similar except for a pad of one part which extends over the ball of the rail, and which is omitted in the other part.

A further object is to provide a rerailer which may be used over a wide range of angles with respect to the tracks and thus be used to replace wheels that are relatively remote from the tracks.

A still further object is to provide a rerailer which may be used to rerail diesel engines without damage to the gear mechanism and to the gear housing commonly used in such locomotives.

A still further object is to provide a rerailer in which the inside and outside sections are each composed of a single integral part which is exceedingly strong, relatively simple to construct and use and which acts to rerail cars and locomotives with a minimum of time and expense.

Other objects and advantages of my invention will become apparent after a study of the following description in connection with the accompanying drawing wherein:

Figure 1 is an elevation of one side of the outside rerailer element.

Figure 2 is an elevation of the other side of the element shown at Figure 1.

Figure 3 is a top plan view of the rerailer element of Figures 1 and 2.

Figure 4 is an end elevation looking from the left of Figures 2 and 3.

Figure 5 is an end elevation looking from the right of Figures 2 and 3.

Figure 6 is a cross-sectional view taken upon a plane indicated by the line 6—6, Figure 2.

Figure 7 is a perspective view, on a reduced scale, of one C clamp used to secure the rerailer to the rail.

Figure 8 is a perspective view, to the same scale as Figure 7, of one wedge used with each clamp.

Figure 9 is a plan view of the right and left rerailer elements or units in operative positions parallel with the tracks and showing in dotted lines various successive positions of the wheels in their replacement upon the tracks.

Figure 10 is a plan view corresponding to Figure 9 but showing the right and left rerailer units

2

when used to rerail wheels which are relatively remote from the tracks.

Figure 11 is a section taken in a plane indicated by the line 11—11 of Figure 10, and

5 Figure 12 is an end elevation of the inside rerailer unit.

It will be understood at the outset, that a complete re-railer set comprises a pair of elements as shown in Figures 9 and 10, one of which is used on the outside of one rail and the other of which is used on the inner side of the other rail, a pair of clamps, one for each element, and a pair of wedges, one for use with each clamp. In my invention the two rerailer elements may be similar except that, as will be subsequently explained, a pad of the outside element is omitted from the inside rerailer.

Each of the two, substantially similar re-railers comprises a base 10 of substantial width as may be seen from Figures 5 and 6. A beam element 11 rises vertically from the base along the central line thereof and is substantially longitudinally co-extensive with the base. See Figure 2. This beam 11 may be of uniform width or thickness throughout its length and of constant height for approximately one-third of the overall length of the rerailer from the forward end thereof, as will be apparent from inspection of Figure 2. Thence the beam 11 decreases in height in a straight line to a point closely adjacent the rear end. From Figures 1 and 5 it will be noted that the outer side of the beam 11 forms a substantially unbroken vertical plane, as indicated at 12, Figures 3, 5, and 6.

35 A heavy wheel-supporting portion indicated generally at 13 Fig. 4 extends to the left from the top of beam 11, as the parts are seen in Figure 5. This portion follows the upper edge of the beam 11 and thus forms an upwardly and forwardly extending incline plane or ramp 13a for about two-thirds of the length of the instrument, succeeded by a generally flat horizontal portion 13b for the remaining forward one-third of the rerailer length. The junction line between these surfaces is indicated at 16, Figures 2, 3, and 10. The parts are so dimensioned that the upper surface of portion 13b is flush with the top of the adjacent rail when base 10 rests on the ties. As indicated at 13c, Figures 2, 3 and 5, the forward 40 inside corner of portion 13b is rounded upon a relatively short radius on the order of 3½ inches. This rounded edge will be in contact with the rail whenever the conditions of use require that the rerailer be positioned at a substantial angle to the track, as in the case where the car wheels

are some distance from the tracks. The top surface of the ramp curves downwardly smoothly on an arc of relatively short radius, say 4", as indicated at 13d, Figures 2 and 3.

A vertical flange or rim 14 extends upwardly from and bounds the ramp portion at the edge thereof adjacent the rail. This flange terminates a little to the rear of the junction line 16, in a vertical knife edge, as indicated at 15, Figures 2 and 3. The other or outside edge of ramp 13a, is bounded or defined by a shoulder 17 whose distance from flange 14 decreases from surface 13a forwardly, and which terminates substantially at the point where rounded edge 13c begins. From Figures 1 and 3 it will be noted that there is a protuberance 18 on the rear portion of wall or plane 12 and that shoulder 17 begins in this protuberance substantially in plane 12. As best shown at Figures 2, 4 and 5, the flange 14 and ramp portion 13d are cut away as indicated at 19, to accommodate the base of the rail so that the rerailer may fit snugly against the rail when such a position is required by the condition of use. A pad 21 is formed on the surface of portion 13b of the outside rerailer and projects therefrom over arcuate surface 13c as plainly shown in Figure 3. The lower surface of this projecting portion of the pad is adapted to rest upon the upper surface of the rail when the rerailer is in use. See Figure 5. A protuberance 20 is located at the forward end of plane 12. The surface 20a, Figure 3, of this protuberance is formed on a relatively long radius say one foot, to provide a surface which may be engaged by a clamp to secure the rerailer, when desired, in an angular relation to the rail, with surface 13c tangent to the vertical plane of the wheel-supporting flange of the rail as clearly shown in Figure 10. A clamp 22 suitable for this purpose is shown at Fig. 7. This clamp is generally C shape. A wedge 23 is shown at Fig. 8 suitable for use in conjunction with the clamp to hold the rerailer in contact with the rail.

As previously explained, two rerailers constitute a set as shown in Figures 9 and 10. Pad 21 is omitted from the inside rerailer.

In use, where the wheels to be rerailed are fairly close to the tracks, the outside rerailer is clamped against the rail just ahead of the derailed wheel, with the projecting portion of pad 21 resting upon the rail and base 10 resting upon the ties. The clamp 22 is then passed under the rail between ties and wedge 23 is driven between the inside end of the clamp and the inner surface of the rail to force the outside end of the clamp against the rerailer and the latter against the rail. The position of one outside rerailer relatively to the rail, will then be as indicated in Figures 5 and 9.

The other, or inside rerailer, is positioned in a corresponding position forwardly of the wheel as shown in Figure 9. However, this inside rerailer is located and clamped in position spaced about one inch from the rail to provide a space for accommodating the flange of the wheel when the wheel moves into proper position upon its rail.

The car is now drawn forwardly and the wheels first contact rear surfaces 13d and thence roll upwardly upon ramp surfaces 13a. As the wheels move upwardly along the ramp surface they are also moved laterally toward the tracks by shoulder 17. As it approaches the upper end of ramp 13a, the flange of the outside wheel

moves onto the horizontal triangular portion 24. Fig. 3, which is flush with the top rail surface. Further movement of the car forwardly causes the wheel to slide along the curved protruding edge of pad 21 and to be shifted laterally thereby until, as it reaches the outer or pointed end of the pad, the flange of the wheel moves into place on the inside of the rail. At the same time, the inside wheel rolls up ramp surface 13a and is at the same time shifted laterally into position by shoulder 17 until, when its flange moves into space between the rerailer and rail, the wheel is correctly positioned. Thus all the wheels of the truck are replaced upon the rails.

When the wheels are relatively remote from the tracks, the outside rerailer is placed with its surface 13d in position aligned with and forwardly of the corresponding wheel and, at the same time its arcuate surface 13c is positioned in contact with and tangent to the ball of the rail. Clamp 22 is then positioned under the rail, between the ties, with one end in contact with arcuate surface 20a, Fig. 3. The wedge is then driven between the other end of the clamp and the rail to hold surface 13c firmly against the rail. The other or inside rerailer is similarly angularly positioned but with a space of about one inch, as aforesaid, between itself and the rail as shown in Figure 10. Because of the arcuate surface 13c, in conjunction with the arcuate clamping surface 20a, the rerailer may be used over a substantial range of angles with respect to the track and may thus successfully rerail wheels which are relatively remote from the tracks.

While I have described the invention in its preferred form of one integral part, it can, of course, be built up from separate pieces bolted or welded together. Since inside and outside rerailers are similar, except for pad 21, the outside rerailers may be completed from an inside rerailer by welding, bolting, or otherwise fixedly securing a pad in position thereon.

The figures of the drawing are substantially to scale and may be referred to if necessary to interpret the range or scope of relative terms and expressions in the claims.

It will thus be evident that I have provided a rerailer which is versatile and easy to use, which does not require spiking in place and which is relatively simple and inexpensive to build. By the use of my rerailer a great deal of time is saved, and the wheels of a car are replaced upon the rails without drop, shock or jar. While I have shown the preferred form of my invention as it is now known to me, various changes in shapes, sizes and arrangement of parts will occur to those skilled in the art after a study of the preceding description. Hence the disclosure should be taken in an illustrative rather than a limiting sense; and it is my intention and desire to reserve all such modifications as fall within the scope of the subjoined claims.

Having now fully disclosed the invention, what I claim and desire to secure by Letters Patent is:

1. A rerailer for replacing derailed flanged wheels of a railway vehicle upon its track, comprising, an elongated block bounded on its sides by first and second spaced parallel vertical planes, said block forming a plane ramp surface rising from one end of the base of said block to a point between the ends thereof, the remainder of said block being of constant height equal to the overall height of the rail, the corner of the other end of said block adjacent said first plane being

rounded, whereby said block may be positioned either with said first plane in contact with the side of the ball of the rail or at an angle to the rail with said rounded corner in contact therewith, there being an upstanding flange in said first plane along one side of said ramp surface, said flange terminating just short of said point, there being a shoulder formed in the top of said block and beginning at said one end substantially in said second plane and extending upwardly and laterally of said ramp surface toward said first plane, said shoulder intersecting said first plane between said point and the other end of said block, said flange and shoulder being of substantially the same height and forming a channel opening through said first plane, and a pad secured over the rounded corner of said block, and having a plane lower surface adapted to extend over the ball of the rail when said block or said rounded corner is in contact therewith.

2. A rerailer as recited in claim 1, said pad having an inner edge forming substantially a continuation of said shoulder.

3. In a rerailer for replacing the wheels of a derailed vehicle upon the rails, a block having a flat base and defining an upwardly-facing smooth ramp surface increasing in height from the plane of said base at one end to a transverse vertical plane positioned from said one end at about two-thirds the normal length of said block, said block defining a second surface extending from the ramp surface and having substantially constant height substantially equal to the height of the rail from said transverse vertical plane to the other end of the block, both said surfaces being bounded at one edge by a longitudinal vertical plane normal to said transverse vertical plane, there being a flat-bottomed channel in said surface having its first side constituting a straight flange parallel to one side of the block and lying in said longitudinal vertical plane and its second side constituting a shoulder uniformly approaching said longitudinal vertical plane upwardly of said ramp surface and intersecting said longitudinal vertical plane between said transverse vertical plane and said other end of the block, said flange terminating just short of said transverse vertical plane, whereby said channel opens laterally through said longitudinal vertical plane, the corner of said surface of substantially constant height being rounded in substantial tangency with said shoulder, whereby said rerailer may be operatively positioned over a substantial range of angles relatively to the rail, with said rounded corner in tangential contact with the side of the ball of the rail.

4. In a rerailer, a one-piece body having opposite side boundary surfaces lying respectively in first and second spaced parallel vertical planes, said body having a ramp surface increasing in height gradually between said planes from one end to about two-thirds of the length of said rerailer followed by a horizontal surface of a height substantially equal to the height of a rail with which the rerailer is intended for use, said surfaces intersecting in a line normal to said planes, the corner of said horizontal surface adjacent said first plane being rounded there being a shallow channel formed in said surfaces and having a first side defined by a flange parallel and lying in said first plane, and a second side beginning closely adjacent said second plane and extending upwardly of said ramp surface and laterally toward said first plane, and terminating tangent to said rounded corner between the ends of said

horizontal surface, said body being shaped so that said rounded corner may be positioned in tangent contact with the ball of the rail over a substantial range of horizontal angles of said body relatively to said rail, and an integral pad on said horizontal surface, a portion of said pad projecting over and outwardly of said rounded corner, the lower exposed surface of said pad being adapted to rest upon the ball of the rail when said rounded corner is in tangential contact with the side thereof.

5. In a rerailer, a one-piece body having opposite side boundary surfaces lying respectively in first and second spaced parallel vertical planes, 15 said body having a ramp surface increasing in height gradually between said planes from one end to about two-thirds of the length of said rerailer followed by horizontal surface of a height substantially equal to the height of a rail with 20 which the rerailer is intended for use, said surfaces intersecting in a line normal to said planes, the corner of said horizontal surface adjacent said first plane being rounded, there being a shallow channel formed in said surfaces and having a first side defined by a flange parallel and lying in said first plane, and a second side beginning closely adjacent said second plane and extending upwardly of said ramp surface and laterally toward said first plane, and terminating tangent to said 25 rounded corner between the ends of said horizontal surface, said body being shaped so that said rounded corner may be positioned in tangent contact with the ball of the rail over a substantial range of horizontal angles of said body relatively 30 to said rail, said body having a projection extending horizontally from said second plane and opposite said rounded corner, said projection having a concave clamp engaging surface whereby to secure said rounded corner in contact with 35 a rail over a substantial range of horizontal angles of said body with respect to the rail.

6. In a rerailer, a one-piece body having opposite side boundary surfaces lying respectively in first and second spaced parallel vertical planes, 45 said body having a ramp surface increasing in height gradually between said planes from one end to about two-thirds of the length of said rerailer followed by a horizontal surface of a height substantially equal to the height of a rail with 50 which the rerailer is intended for use, said surfaces intersecting in a line normal to said planes, the corner of said horizontal surface adjacent said first plane being rounded, there being a shallow channel formed in said surfaces and having a first side defined by a flange parallel and lying in said first plane, and a second side beginning closely adjacent said second plane and extending upwardly of said ramp surface and laterally toward 55 said first plane, and terminating tangent to said rounded corner between the ends of said horizontal surface, said body being shaped so that said rounded corner may be positioned in tangent contact with the ball of the rail over a substantial range of horizontal angles of said body relatively to said rail, and a pad on said horizontal surface, a portion of said pad projecting over and outwardly of said rounded corner, the lower exposed surface of said pad being adapted to rest upon the ball of the rail and the side edge of the 60 projecting portion of said pad being substantially a continuation of the second side of said channel.

7. A rerailer for replacing derailed flanged wheels of a railway vehicle upon its track, comprising, an elongated block bounded on its sides

by first and second spaced parallel vertical planes, said block forming a plane ramp surface rising from one end of the base of said block to a point between the end thereof, the remainder of said block being of constant height equal to the overall height of the rail, the corner of the other end of said block adjacent said first plane being rounded, whereby said block may be positioned either with said first plane in contact with the side of the ball of the rail or at angle to the rail 10 with said rounded corner in contact therewith, there being an upstanding flange in said first plane along one side of said ramp surface said flange terminating just short of said point, there being a shoulder formed in the top of said 15 block and beginning at said one end substantially in said second plane and extending upwardly and laterally of said ramp surface to-

ward said first plane, said shoulder intersecting said first plane between said point and the other end of said block, said flange and shoulder being of substantially the same height and forming a channel opening through said first plane.
